FILLING-FEELER FOR LOOMS.

1,249,276.

Specification of Letters Patent.

Patented Dec. 4, 1917.

Application filed April 5, 1915. Serial No. 19,282.

To all whom it may concern:

Be it known that we, CLARE H. DRAPER and JONAS NORTHROP, citizens of the United States, residing at Hopedale, in the county 5 of Worcester and State of Massachusetts, respectively, have invented certain new and useful Improvements in Filling-Feelers for Looms; and we do hereby declare the following to be a full, clear, and exact description 10 of the invention, such as will enable others skilled in the art to which it appertains to make and use the same.

The present invention relates to an improvement in filling feeler mechanisms for 15 looms. In the weaving of high-grade fabrics it is desirable to have a fresh filling inserted in the shuttle before the old filling is entirely exhausted. It is undesirable, however, that a bobbin containing a large 20 amount of unused filling should be ejected from the shuttle, both because of the waste of filling material and because of the loss of time spent in stripping the unused filling from the bobbin. The object of the present 25 invention, then, is to produce a filling feeler mechanism which will operate to cause a filling replenishment when the filling on the bobbin has been exhausted to an extent beyond which it is unsafe to exhaust the filling, 30 because of the liability of weaving a short weft thread into the fabric.

To this end the present invention contemplates a filling feeler mechanism in which the member for determining the 35 amount of filling on the bobbin is caused to travel along and in engagement with the smooth surface of the unwound portion of the bobbin, and engage the end winding of the filling until the filling has been exhausted 40 to a predetermined extent, that is, as nearly as it is practicable to approximate to an amount sufficient for three picks only, whereupon the filling replenishment mechanism is set in operation.

In the accompanying drawings illustrating the preferred embodiment of the present invention, Figure 1 is a plan of a portion of the left-hand end of a loom showing the improved filling feeler mechanism attached 45 thereto and the appurtenant parts of the loom, the feeler being shown in the position of first contacting with a filled bobbin; Fig. 2 is a plan similar to Fig. 1, showing

the position of the filling feeler when the lay has reached its full forward beat; Fig. 55 3 is a plan of the filling feeler mechanism showing the positions of the parts at predetermined exhaustion of the filling; Fig. 4 is a front elevation with the parts in the positions of Fig. 3; Fig. 5 is a side elevation 60 with the parts in the positions of Fig. 1 looking from left to right, with a portion of the shuttle broken away to show that part of the shuttle with which the filling feeler controller contacts; Fig. 6 is a view 65 similar to Fig. 5 with the controller removed and the end of the filling feeler and the slide supporting plate shown in section; and Fig. 7 is a detail view of the filling engaging member.

The loom to which the improved filling feeler mechanism is attached may be of any usual or preferred construction, and comprises a frame 10, a breast beam 11, a lay 12 carried by a sword 13, a detector arm 14 75 mounted on the usual rock shaft 15 for setting the weft supply mechanism in operation, a weft hammer 17, a detector fork 18 and other usual and appurtenant parts. The shuttle 19 is provided with the usual 80 slot 20 in its front wall. The improved filling feeler mechanism operates upon the exhaustion of the filling on the bobbin, or filling carrier, to a predetermined extent to draw the weft replenishing actuator 22 to 85 the left into the path of an arm or finger 23 on the weft hammer 17 which, on a forward beat, pushes forward the actuator 22 and the detector arm 14 thereby actuating the rock shaft to effect the insertion of a fresh filling 90 in the shuttle.

The improved filling feeler mechanism comprises a filling feeler which consists of a feeler lever 24 and a filling engaging member 53 and a filling feeler controller 25 95 mounted upon a slide 26, which is adapted to reciprocate forwardly and backwardly upon a slide-supporting plate 27. The slide-supporting plate 27 is provided with a downward extension which is secured to a bracket 100 28 supported by the breast beam 11. The slide 26 is provided on its under side with a rib or keel 30 which is received in a slot 31 running longitudinally of the plate 27. The keel has a depending boss 32 provided 105 with a hole which receives a cotter pin to

- prevent upward movement of the forward end of the slide. A vertical pin 33 secured in the rearward portion of the slide 26 is provided with a shoulder 34 which prevents 5 upward movement of the rearward end of the plate. The lower end 35 of the vertical pin 33 is provided with a hole in which is rigidly and adjustably secured a rod 36 of which the forward end is loosely received in 10 a boss 37 depending from the forward end of the slide-supporting plate 27. A helical spring 38 embracing the rod tends to maintain the slide 26 in rearward position toward the shuttle. The extent of the rearward or shuttleward movement of the slide 26 is determined by the engagement of a boss 40, which extends downward from the shoulder 41 of the filling feeler, with a boss 43 extending up from the forward end of 15 the slide-supporting plate 27.
- The filling feeler controller which is adapted to be struck by some structure carried by the lay and having a fixed position relatively to the bobbin—in this instance by 20 the bobbin-holding jaws 45—screws into a boss 46 projecting from the slide 26. A nut 47 serves to maintain the controller in adjusted position. The filling feeler is mounted upon the vertical pin 33 and is adapted to 25 turn thereon under the propulsion of a spring 48 of which the forward end is received in a hole in the shoulder 41 of the filling feeler, the other end of the spring being received in a hole in the boss 49 on the slide 26. The 30 filling feeler is provided with a forwardly extending tongue or cam actuator 50. When there is a substantial amount of filling upon the bobbin, the controller 25 is not engaged by the shuttle; the filling covered 35 bobbin, however, engages the filling feeler upon the forward beat of the lay. Inasmuch as the pressure exerted upon the filling feeler is to the right of its fulcrum the filling feeler tends to rotate clockwise, 40 whereupon the tongue or cam actuator 50 is pushed against a boss 51 on the slide 26, so that, as the lay continues its forward beat the cam actuator is carried forward 45 inoperatively from the position shown in 50 Fig. 1 to the position shown in Fig. 2. When, however, the filling is exhausted nearly to its predetermined extent, the controller is struck by the shuttle on the forward beat of the lay, and serves to push the 55 slide forward, thereby relieving the filling feeler of that function. The filling feeler, no longer receiving any end thrust, tends to move anti-clockwise under pressure by the spring 48.
- 60 The filling feeler is provided upon its filling-engaging end with the filling engaging member 53 which is slidably mounted upon the feeler lever 24 and is yieldingly pressed toward the lay. The filling engaging member 65 comprises a head piece 53 and a shank
54. The head piece has a smooth, angularly inclined face 55 tapering from the left forwardly toward the right. The acute angle formed between the left-hand side of the head and its face serves as a tooth 56 to engage the filling. The shank is bifurcated for the admission of a spring 57, the forward end of which takes against the rib 58 in the feeler lever, while the rear end takes against the inner face of the filling 70 engaging member. The pin 59 passing through the sides of the shank engages the rib 58 and limits the movement of the filling engaging member toward the bobbin. Inwardly extending lateral ledges 60 on the 75 feeler lever provide bearing surfaces for the shank. It will be noted that when the filling engaging member is in normal position as shown in Fig. 7, a space separates it from the end of the feeler lever.
- 85 The connections through which the filling feeler mechanism operates to draw the detector arm actuator 22 to the left comprise a connecting rod 62 of which the right-hand end is loosely attached to the detector arm actuator 22 in such manner as to prevent the rod from rotating, the left-hand end of the rod being slidably supported in a bearing in an upright 63 on the slide-supporting plate 27. The connecting rod is actuated 90 by two complementary cam members provided with corresponding V-shaped cam surfaces. The fixed cam member 65 is rigidly secured to the left-hand end of the connecting rod by means of the set screw 66, while the rotary cam member 67 is loosely mounted thereon. The rotary cam 67 is provided with a downwardly extending lug 68 which is adapted to be struck by the cam actuator 50 on a forward beat of the lay, when the filling is exhausted to a predetermined extent. A helical spring 69, of which one end takes against the upright 63 and the other against an adjustable collar 70, tends to force the fixed cam member 65 against the 95 rotary cam member 67 and the latter against the upright 63, which limits the rightward movement of the connecting rod. When the cam lug 68 of the rotary cam 67 is struck by the cam actuator 50 and pushed forward, 100 it is rotated upon the connecting rod 62 so as to force the fixed cam member to the left, thereby drawing the detector arm actuator 22 into the path of the finger 23 mounted on the weft hammer 17.
- 105 The operation of the improved filling feeler mechanism is described as follows: So long as a substantial amount of filling remains upon the bobbin the filling engaging member 53 is engaged by it, and upon the continued forward beat of the lay the cam actuator 50 is carried forward inoperatively. When, however, the filling has become exhausted nearly to a predetermined extent the filling feeler controller is struck 110
- 115
- 120
- 125
- 130

- by the bobbin-holding jaws 45 and thereupon the filling feeler, relieved of end pressure, tends to turn upon its pivot and move toward the left, the cam actuator 50 moving toward the right to its operative position behind the cam lug 68. This pivotal movement of the filling feeler whereby its filling engaging end is caused to move longitudinally of the bobbin or filling carrier is known as the filling feeler movement of the filling feeler. The cam actuator is not brought behind the cam lug immediately the controller is struck by the shuttle, for the reason that as the filling engaging member of the filling feeler travels toward the left along and in engagement with the surface of the bobbin, it is arrested by engagement with the end winding of the filling, and upon each successive detecting pick it is likewise arrested as long as sufficient filling remains on the bobbin. When finally the filling has been exhausted to a predetermined extent, and therefore to a predetermined point toward the butt of the bobbin, the filling engaging member will have traveled toward the left sufficiently to bring the cam actuator behind the cam lug; thereupon the forward beat of the lay causes the cam actuator to engage the lug and push it forward out of its path of travel, thereby causing the connecting rod 62 to be forced to the left and the detector arm actuator to be brought into the path of the finger 23, so that, upon the next forward beat of the weft hammer, the detector arm actuator 22 and the detector arm are pushed forward, rotating the rock shaft 15 and setting in operation the weft supply mechanism.
- It will be observed that while the filling feeler is swinging toward the left it also travels forwardly. The effect of this double simultaneous movement of the filling feeler is to cause it to travel along the surface of the bobbin in substantially a straight line. But inasmuch as there is a slight curvature in this movement of the filling-engaging end of the filling feeler, the filling-engaging end would have a tendency to leave the bobbin, were not provision made for causing it always to travel along and in engagement with the surface of the bobbin after the filling thereon has been sufficiently exhausted. Moreover, there are variations in the size of the bobbins; and sometimes, too, a bobbin is positioned obliquely or eccentrically in the shuttle, making it also necessary to provide means for compensating for the different sizes of bobbins and obliquely positioned bobbins. In order, then, that the slight curvature in the movement of the filling-engaging end of the filling feeler, and the variations in the size of the bobbins, and an occasionally obliquely positioned bobbin, may not affect the accuracy of the operation of the filling feeler, the filling feeler is provided with a filling engaging member which is spring-pressed toward the bobbin as hereinbefore described. The longitudinal movement of this member on the feeler lever is sufficient to compensate for the variations in the sizes of the bobbins and also for an obliquely positioned bobbin, so as to cause the filling-engaging tooth 56 to travel along and in engagement with the surface of the bobbin and engage the end winding of the filling in the manner hereinbefore described. This filling engaging member forms the chief feature of the invention.
- Another feature of the invention resides in the coöperative action of the filling feeler controller 25 and the filling feeler 24. The advantages of this coöperative action are apparent when it is considered that the chief function of the filling feeler resides in determining the extent to which the filling has been exhausted, and that the function of the controller resides in receiving the thrust of the advancing shuttle, first, to permit the filling feeler to turn on its fulcrum and follow the receding end winding of the filling, and secondly, to carry forward the operatively positioned cam actuator to set in operation the filling supply mechanism. So that, in the coöperative action of the two members we have, first, the filling feeler engaged by the filling on the bobbin, to carry the cam actuator forward inoperatively until the filling approaches the predetermined point of exhaustion, at which point the controller comes into operation; secondly, upon the approach of the filling to its predetermined exhaustion, the striking of some fixed portion of the shuttle against the controller, and the consequent tendency of the filling engaging member to travel along the exposed surface of the bobbin in following the unwinding filling; and, finally, upon the exhaustion of the filling to a predetermined point on the bobbin, the arrival of the filling engaging member at that point and the simultaneous arrival of the cam actuator in its operative position behind the cam lug; and, coincident thereto, the forward movement of the cam actuator to effect a filling replenishment.
- From the foregoing description it appears that the filling feeler controller is not brought into operation until the filling is quite near its predetermined extent of exhaustion. Its time of operation, then, depends upon the extent to which the filling has been exhausted, as determined by the filling feeler. And since the shuttle or some fixed surface thereon does not strike the controller until the filling covered bobbin no longer strikes the filling feeler and pushes it forward, and the filling feeler cannot turn on its fulcrum until the shuttle strikes the controller, it may be said that the filling feeler determines the time of operation of the

controller, and that the time of operation of the controller governs the time of the rotative movement of the filling feeler.

The utilization of the rotative motion of the filling feeler longitudinally of the bobbin or filling carrier in determining the extent to which the filling shall be exhausted before a fresh filling is inserted in the shuttle, results in all of the bobbins being emptied to a uniform degree, and for this reason:— The filling engaging member of the filling feeler travels along and in engagement with the smooth surface of the bobbin under the propulsion of a delicate spring whose expansive movement is arrested by the slightest obstruction in the path of the filling engaging member. Consequently, the bobbin must be unwound to substantially a fixed point from its butt before the filling feeler can swing far enough toward the left to permit the cam actuator to be operatively positioned.

Viewed in its broader aspects, the invention is not limited to the use of any specific form of feeler controller or means for holding the filling feeler in normal position until the latter has been engaged by the filling carrier. The invention is broad and generic in character, and constitutes a distinct and important advance in the filling feeler art, inasmuch as it is the first filling feeler mechanism wherein the filling-engaging end of the filling feeler is caused to move longitudinally of the filling carrier in engagement with the denuded surface thereof and with the end winding of the exhausting filling. The invention may be embodied in forms of mechanism other than that specifically described herein and still be within the scope of the claims.

It is to be noted that the word bobbin has been used herein as defining the particular form of filling carrier illustrated in the drawings. The invention is not limited to constructions employing this particular form of filling carrier as other filling carriers may be used if desired.

Having thus described our invention, what we claim is:—

50. 1. A filling feeler mechanism for looms comprising a pivoted feeler member mounted to yield with the lay, means for normally holding the feeler member in position to be engaged by the filling and in position so as not to affect the loom operation, and means operative on predetermined exhaustion of filling to turn the feeler member to effect a change in the loom operation, said feeler member being arranged so that the pressure of the filling carrier against it tends to turn it in a direction opposite to that in which it turns to effect a change in the loom operation.
60. 2. A filling feeler mechanism for looms having, in combination, a pivoted filling

feeler, means for normally holding the feeler in position to be engaged by the filling carrier, and means for turning the feeler upon predetermined exhaustion of filling, the filling engaging end of said feeler being offset to one side of the pivot so that the pressure of the filling carrier against it tends to turn the feeler in a direction opposite to that in which the feeler turning means turns it.

3. A filling feeler mechanism for looms having, in combination, a filling feeler mounted for reciprocating and swinging movements, means for holding the filling feeler in normal position until the latter has been engaged by the filling carrier, and means for imparting the reciprocating and swinging movements to the filling feeler, said filling feeler being constructed and arranged so that as it swings its filling engaging end presses against and moves along the denuded surface of the filling carrier and is controlled by the unwinding filling.

4. A filling feeler mechanism for looms comprising a feeler lever, a filling engaging member slidably and yieldingly mounted on the feeler lever and arranged to receive the pressure of the filling carrier, means operating to turn the feeler lever when the filling approximates predetermined exhaustion, and means for rendering ineffective the feeler lever turning means while the feeler lever is in normal position.

5. A filling feeler mechanism for looms comprising a feeler lever, a filling engaging member slidably mounted on the feeler lever and yieldingly pressed toward the filling carrier to receive the impact of the filling carrier, means rendered operative to turn the feeler lever when the filling approximates predetermined exhaustion, and means for rendering ineffective the feeler lever turning means while the feeler lever is in normal position, said filling engaging member having a range of movement such that it constantly engages and travels along the denuded surface of the filling carrier while the feeler lever performs its turning movement.

6. A filling feeler mechanism for looms comprising a feeler lever, means operating to turn the feeler lever when the filling has been exhausted to a predetermined extent, means rendering the feeler lever turning means inoperative so long as the feeler lever is not engaged by the filling carrier, and a filling engaging member slidably and yieldingly mounted on the feeler lever to receive the impact of the filling carrier.

7. A filling feeler mechanism for looms comprising a feeler lever, means for preventing the turning of the feeler lever until it has been engaged by the filling carrier, whereupon the engagement of the filling with the feeler lever prevents the turning of the feeler lever until predetermined ex-

- haustion of the filling, means effective upon predetermined exhaustion of the filling to turn the feeler lever, and a filling engaging member slidably and yieldingly mounted on the feeler lever having a range of movement permitting it to press against and travel along the denuded surface of the carrier while the feeler lever is performing its turning movement.
10. 8. A loom having, in combination, a lay, a shuttle, a filling carrier, and a filling feeler mechanism comprising a filling feeler constructed and arranged to engage and move along the denuded surface of the filling carrier in engagement therewith and with the filling when the filling has been exhausted to a predetermined extent and to be arrested in its longitudinal movement by the filling until the latter is exhausted to a predetermined point from the butt of the filling carrier, means for actuating the feeler, and means for holding the feeler in normal position until it has been engaged by the filling carrier.
25. 9. A filling feeler mechanism for looms comprising a slide, a feeler lever mounted thereon, a filling engaging member slidably and yieldingly mounted on the feeler lever and arranged to receive the impact of the filling carrier to move the slide forward until the filling approaches predetermined exhaustion, and a feeler controller fixed on the slide and arranged to be engaged by the shuttle to move the slide forward when the filling approaches predetermined exhaustion, the range of movement of the filling engaging member relatively to the feeler lever being such that it continues to engage the filling carrier while the slide is pushed forward by the feeler controller, but does not communicate any pressure from the filling carrier to the feeler lever.
10. A filling feeler mechanism for looms comprising a feeler lever mounted to swing in a plane substantially parallel with the horizontal plane of the filling carrier, having an arm arranged to project into the shuttle and engage with the filling carrier to determine the amount of filling thereon, means for actuating the feeler lever to turn it and thereby cause its filling engaging end to move lengthwise of the filling carrier, means for holding the feeler lever actuating means inoperative until the filling carrier has engaged the feeler lever, and a filling engaging member mounted on the feeler lever arm and yieldingly pressed toward the filling carrier having a range of movement permitting it to engage and travel along the denuded surface of the filling carrier when the feeler lever is turned by its actuating means.
11. A loom having, in combination, a lay, a shuttle, a filling carrier, and a filling feeler mechanism comprising a filling feeler adapted to have a filling feeling movement longitudinally of the filling carrier, said filling feeler consisting of a feeler lever and a filling engaging member slidably mounted on the feeler lever and yieldingly pressed toward the lay, and adapted on predetermined exhaustion of filling to move along the denuded surface of the filling carrier in engagement with the end winding of the filling and to be arrested thereby until the filling is exhausted to a predetermined distance from the butt of the filling carrier, means for imparting the filling feeling movement to the filling feeler, and means for holding the filling feeler in normal position until it is engaged by the filling carrier.
12. A filling feeler mechanism for looms comprising a support, a slide mounted on the support for movements toward and from the lay, a feeler lever pivoted on the slide arranged to be engaged by the filling carrier on each filling feeling beat to move the slide forward until the filling approaches predetermined exhaustion, a feeler controller fixed on the slide and arranged to be struck by the shuttle to move the slide forward when the filling approaches predetermined exhaustion to relieve the feeler lever of the pressure of the filling carrier, means operating to turn the feeler lever as the filling approaches predetermined exhaustion, and a filling engaging member yieldingly mounted on the feeler lever and having a range of movement permitting it to engage the filling carrier when the slide is moved forward by the engagement of the shuttle with the feeler controller.
13. A filling feeler mechanism for looms comprising a support, a slide mounted on the support, a feeler lever on the slide, a feeler controller fixed on the slide, means rendered effective when the filling has been exhausted to a predetermined extent to turn the feeler lever, and a filling engaging member yieldingly mounted on the feeler lever having a range of movement such that as the feeler lever is turning, the filling engaging member engages and travels along the denuded surface of the filling carrier, being arrested in its traveling movement by the end windings of the exhausting filling.
14. A filling feeler mechanism for looms comprising a support, a slide mounted on the support and yieldingly pressed toward the lay, a feeler lever pivoted on the slide, a feeler controller fixed on the slide and arranged to be struck by the shuttle to move the slide when the filling approaches predetermined exhaustion to permit the feeler lever to turn, means rendered effective when the filling approximates predetermined exhaustion to turn the feeler lever, and a filling engaging member yieldingly mounted on the feeler lever and arranged to receive the pressure of the filling carrier to move the

- slide forward until the filling approaches predetermined exhaustion, said filling engaging member having such range of movement that it continues to engage the filling carrier and travel along its denuded surface as the feeler turns.
15. A filling feeler mechanism for looms comprising a support, a slide yieldingly mounted thereon for movements toward and 10 from the lay, a feeler lever pivoted on the slide, a filling engaging member yieldingly mounted on the slide arranged to be engaged by the filling carrier to move the slide forward until the filling approaches predetermined exhaustion, a feeler controller fixed 15 on the slide and arranged to be struck by the shuttle when the filling approaches predetermined exhaustion to move the slide forward, thereby relieving the feeler lever of the pressure of the filling carrier, said filling 20 engaging member having such a range of movement on the feeler lever that it continues to engage the filling carrier on the filling feeling beats, and means rendered operative to turn the feeler lever when the part 25 of the filling carrier opposite the filling engaging member has been completely denuded of filling, the turning movements of the feeler lever being arrested by the engagement of the filling engaging member with the end 30 windings of the filling until the latter has reached a predetermined point from the butt of the filling carrier.
16. A loom having, in combination, a lay, 35 a shuttle, a filling carrier, and a filling feeler mechanism comprising a filling feeler adapted to have a filling feeling movement longitudinally of the filling carrier and in engagement with the denuded surface thereof, said filling feeling movement of the filling 40 feeler being controlled in its longitudinal movement by the exhausting filling, means for imparting the filling feeling movement to the filling feeler when the filling 45 is exhausted to a predetermined extent, and means for holding the filling feeler in normal position until it has been engaged by the filling carrier.
17. A loom having, in combination, a lay, 50 a shuttle, a filling carrier, and a filling feeler mechanism including a pivoted filling feeler, means to impart a yielding filling feeling movement to the filling feeler, and a filling engaging member yieldingly mounted 55 on the filling feeler.
18. A loom having, in combination, a lay, 60 a shuttle, a filling carrier, and a filling feeler mechanism including a filling feeler, a filling engaging member yieldingly mounted on the filling feeler, and means for moving the filling feeler lengthwise of the filling carrier.
19. A loom having, in combination, a lay, 65 a shuttle, a filling carrier, and a filling feeler mechanism including a filling feeler
- having a spring actuated filling feeling movement lengthwise of the filling carrier, and a filling engaging member yieldingly mounted on the filling feeler having provision for traveling along the unwound surface of the filling carrier when the filling thereon has been exhausted to a predetermined extent.
20. A loom having, in combination, a lay, 70 a shuttle, a filling carrier, and a filling feeler mechanism having a reciprocating slide, a filling feeler provided with an independently yielding filling engaging member mounted upon the slide, and means to cause a change in the operation of the loom on movement of the slide when the filling on the filling carrier has been exhausted to a predetermined extent.
21. A loom having, in combination, a lay, 75 a shuttle, a filling carrier, and a filling feeler mechanism having a reciprocating slide, a filling feeler adapted to move lengthwise of the filling carrier provided with an independently yielding filling engaging member mounted upon the slide, and means to cause a change in the operation of the loom on 80 movement of the slide when the filling on the filling carrier has been exhausted to a predetermined extent.
22. A loom having, in combination, a lay, 85 a shuttle, a filling carrier, and a filling feeler mechanism comprising a feeler lever having an independently yielding filling engaging member reciprocatingly mounted on the feeler lever adapted to move along the 90 surface of the filling carrier in engagement with the end winding of the filling and to be arrested in its longitudinal movement thereby until the filling is exhausted to a predetermined distance from the butt of the 95 filling carrier.
23. A loom having, in combination, a lay, 100 a shuttle, a filling carrier, and a filling feeler mechanism comprising a feeler lever adapted to have a filling feeling movement longitudinally of the filling carrier, a filling 105 engaging member yieldingly and reciprocatingly mounted on the feeler lever adapted to move along the surface of the filling carrier in engagement with the end winding 110 of the filling and to be arrested thereby until the filling is exhausted to a predetermined distance from the butt of the filling carrier, and a controller for the feeler lever.
24. A loom having, in combination, a lay, 115 a shuttle, a filling carrier, and a filling feeler mechanism comprising a filling feeler adapted to move along and in engagement with the denuded surface of the filling carrier in engagement with the end winding of 120 the filling and to be arrested in its longitudinal motion thereby until the filling is exhausted to a predetermined distance from the butt of the filling carrier, and a controller for the feeler.
- 125
- 130

25. A loom having, in combination, a lay, a shuttle, a filling carrier, and a filling feeler mechanism including a filling feeler adapted to engage the unwound surface of the filling carrier when the filling thereon has been exhausted to a predetermined extent and to travel along the unwound surface toward the butt end of the filling carrier in engagement with the end winding of the filling, and means for causing the filling feeler to travel along the unwound surface of the filling carrier.
26. A loom having, in combination, a lay, a shuttle, a filling carrier, and a filling feeler mechanism including a filling feeler yieldingly held against the filling carrier during the filling feeling operation, and means to cause the filling feeler to travel along and in engagement with the unwound surface of the filling carrier when the filling thereon has been exhausted to a predetermined extent.
27. A filling feeler mechanism for looms having, in combination, a filling feeler, a feeler controller having provision for holding the filling feeler in normal position until the latter has been engaged by the filling carrier, and means for imparting a reciprocatory and a swinging movement to the filling feeler, said filling feeler being constructed and arranged so that as it swings it travels along and in engagement with the denuded surface of the filling carrier, being controlled in its swinging movement by the unwinding filling.
28. A loom having, in combination, a lay, a shuttle, a filling carrier, and a filling feeler mechanism including a filling feeler adapted, when the filling on the filling carrier has been exhausted to a predetermined extent, to have a filling feeling movement longitudinally of and in engagement with the unwound surface of the filling carrier and with the end winding of the filling, and to be arrested by the latter until the filling has been exhausted to a predetermined point from the butt end of the filling carrier, and means for imparting the filling feeling movement to the filling feeler.
29. A loom having, in combination, a lay, a shuttle, a filling carrier, and a filling feeler mechanism including a movable filling feeler having provision for movement transversely of the filling carrier until the filling thereon has been exhausted to a predetermined extent, and having provision for pivotal movement when the filling on the filling carrier has been exhausted to a predetermined extent, said filling feeler having a filling engaging part constructed and arranged to be yieldingly pressed against the unwound surface of the filling carrier so as to engage the end winding of the filling during the pivotal movement of the filling feeler.
30. A filling feeler mechanism for looms having, in combination, a filling feeler mounted for reciprocatory and swinging movements, means for reciprocating the feeler, means operative to swing the feeler when the filling approaches predetermined exhaustion, and means for yieldingly pressing the feeler toward the lay and holding it in normal position until it has been engaged by the filling carrier, said feeler being constructed and arranged so that as it swings its filling engaging end presses against and moves along the denuded surface of the filling carrier in engagement with the exhausting filling.
31. A filling feeler mechanism for looms having, in combination, a filling feeler having its filling-engaging end arranged for movement both transverse to the filling carrier and longitudinally thereof, means for holding the filling feeler in normal position until it has been engaged by the filling carrier, and means for imparting transverse and longitudinal movements to the filling-engaging end of the filling feeler, said feeler being constructed and arranged so that as it moves longitudinally its filling-engaging end presses against and moves along the denuded surface of the filling carrier and is controlled by the unwinding filling.
